(57) **CLAIM**

The ornamental design for a chemiluminescence compact imaging scanner lid, as shown and described.

DESCRIPTION

FIG. 1 is a perspective view of a chemiluminescence compact imaging scanner lid showing our new design;

FIG. 2 is a front elevational view;

FIG. 3 is a rear elevational view;

FIG. 4 is a left side elevational view;

FIG. 5 is a right side elevational view;

FIG. 6 is a top plan view thereof;

FIG. 7 is a bottom plan view partially occluded by a scanner base; and,

FIG. 8 is a perspective view showing a bottom of the design. Portions or features of the chemiluminescence compact imaging scanner lid not shown in the drawings form no part of the claimed design. Broken lines and entirely unshaded portions contained within broken line are not claimed. Views that are not shown are not claimed.

The chemiluminescence compact imaging scanner lid is intended for use as a light-tight cover lid for a scanner that images molecular biology assays exhibiting chemiluminescence or other luminescence.
